UNITED STATES PATENT OFFICE.

CHARLES M. LEVY, OF NEW YORK, N. Y.

RING.

No. 840,946.

Specification of Letters Patent.

Patented Jan. 8, 1907.

Application filed August 7, 1906. Serial No. 329,528.

To all whom it may concern:

Be it known that I, CHARLES M. LEVY, a citizen of the United States of America, residing at New York, in the county of New York and State of New York, have invented certain new and useful Improvements in Rings, of which the following is such a full, clear, and exact description as will enable others skilled in the art to which it appertains to make and use the same.

This invention has special reference to signet locket-rings, and seeks to provide a construction which will permit the locket-ring to retain the usual appearance of a signet-ring, will permit the usual ornamentation of the band adjacent to the seal, will possess a high degree of strength, and will provide water-tight joints around the picture or other memento placed in the locket.

To this end the invention consists in certain novel features illustrated in the accompanying drawings and hereinafter first fully described, and then particularly pointed out in the claim.

In the drawings, Figure 1 is a perspective view of a ring embodying my invention. Fig. 2 is a longitudinal section of the same. Fig. 3 is a transverse section of the ring with the seal and box removed, and Fig. 4 is an enlarged longitudinal section of the particular portion of the ring containing my improvements.

The annular shank or band 1 is given the usual conformation of a signet-ring; but the top or seal portion is made hollow, as shown at 2. The top of this seal portion presents an elliptical opening 3, having its entire edge in a single plane and arranged transversely of the shank. On the inner face of the wall 40 of the band at one side of the opening and just below the edge of the same is a minute recess 4, and directly opposite the said recess the band is provided with two small perforated lugs or ears 5. A box is constructed to fit snugly in this elliptical opening 3 and comprises a base 6 and a straight bezel 7, depending from the inner face of the base, the bezel having a small projection or tooth 8 struck up on one side to engage the recess 4, while diametrically opposite said tooth or projection a small perforated lug or ear 9 is formed on the edge of the base, which ear fits closely between the perforated lugs 5 on the annular shank. A pivot-pin 10 is inserted 55 through the registering openings in these

lugs, and thereby joins the box to the band by a hinged connection, the ends of the pin being beveled and finished off close to the surface of the band, so as to merge into the ornamentation 11 thereon. A picture or other memento 12 is placed against the inner face of the base 6 and within the bezel 7, and a glass 13, having a beveled edge, is placed over the picture, after which the edge of the bezel is burnished down over the beveled edge of the glass, so as to firmly secure the same and form a water-tight joint therewith. A lid or seal 14 is soldered on the outer face of the base 6 and has its edge projecting beyond the edge of the base a distance equal to the thickness of the wall of the band or annular shank, so that the seal or lid will cover the joint between the box and the band and its edge will merge into the surface of the band, whereby the finished article will have the appearance of a solid ring. The outer face of the lid or seal may be engraved in the usual manner or may be ornamented with precious stones.

From the foregoing description, taken in connection with the accompanying drawings, it will be seen that I have provided a signet-ring containing a locket in which may be placed a picture or other memento. When the locket is closed, the ring will have the appearance of an ordinary signet-ring, and the usual ornamentation may be applied without being marred by the entrance of long joints thereinto, the only outside joint being practically invisible and having the appearance of a thin line drawn around the edge of the seal as a part of the scheme of ornamentation. By having the bezel of the same shape as the opening in the shank and fitting closely in the same the shank or band is not weakened, but is reinforced and braced or strengthened by the bezel and box. The metal will possess sufficient natural resiliency to yield as the box is closed into the ring and permit the projection 8 to ride into engagement with the recess 4, and the engagement of the said recess and projection will hold the lid tightly against the ring and prevent the access of water to the interior. The box will thus be held firmly closed against accidental opening, but at the same time may be easily opened when a slight pressure is properly applied to the edge of the lid over the lug 8.

Having thus described my invention, what

I claim, and desire to secure by Letters Patent, is—

A finger-ring having a recessed annular shank provided with an elliptical transversely-disposed opening in its outer side, an elliptical base having one edge hinged to one side of said opening, a bezel depending from the base and fitting snugly in said opening, the bezel being constructed to lockingly engage the wall of the opening opposite the hinge, a beveled-edge glass within the bezel, the edge of the bezel being bent over and

down upon the edge of the glass, and an elliptical seal secured on the outer face of the base with its edge projecting beyond the edge of the base to rest upon the wall of the opening and merge into the surface of the shank. 15

In testimony whereof I have signed this specification in the presence of two subscribing witnesses.

CHARLES M. LEVY.
